UNITED STATES PATENT OFFICE

EARL S. ALEXANDER, OF IRVINGTON, NEW JERSEY, ASSIGNOR, BY MESNE ASSIGNMENTS, TO VACUUM SPECIALTIES CORPORATION, OF JERSEY CITY, NEW JERSEY, A CORPORATION OF NEW JERSEY

AIR VENT FOR RADIATORS

Application filed December 13, 1928. Serial No. 325,749.

This invention relates to an improved air vent for radiators which is constructed so that it is closed by an increase in temperature or by the entry of a material amount of water into the casing of the valve or vent.

The improvement resides in a mounting for the thermostatic elements and an adjustable means accessible from the outside of the casing, these parts being economically produced and easily assembled.

Another feature of the invention is a breather which is used when necessary as an auxiliary to the main valve which breather acts, especially in vacuum systems, to prevent the return of air to the heating system when the fluid in the system becomes cooler after heating.

The invention also has for its object the provision of a thermostatic member and a valve operated thereby and a support for the thermostatic member, all these acting to vibrate the valve slightly when it closes and when it opens. This movement rubs the valve slightly on its closing and opening, assures its seating and keeps the valve clean.

The invention is illustrated in the accompanying drawings in which Figure 1 is a cross-section of an air valve embodying my invention. Figure 2 is a section on line 2-2 in Figure 1 and Figure 3 is a section on line 3-3 in Figure 1.

The valve comprises any suitable form of casing and I show one comprising a barrel 10 with a base 11 having the usual screw-threaded lug 12 with the inlet passage 13. This lug is screwed into the radiator wall and I may use the siphon pipe 14 if desired. On the top of the casing is the plate or partition 15.

In the chamber of the casing is the stem 16 which supports the valve thimble 17 which in turn is secured to the dome 18. The spider 19 at the bottom of the dome and engaging the stem 16 prevents the dome from engaging the side walls of the casing and this prevents capillary attraction and consequent rise of water in the valve. The dome is provided with longitudinal grooves 20 for the same purpose and for the further purpose of allowing enough vent to prevent a sudden gust of

air to force the dome suddenly upward to close the valve. The valve 21 is at the top of the stem, as on the thimble 17 and is disposed so that when it rises it closes the opening 22 in the top 55 plate 15.

Arranged between the bottom of the thimble 17 and a suitable stop such as the shoulder or plate 23 is a series of thermostatic strips each strip 24 being bent into 60 curved form and arranged one on the other. The preferred form is one of a U-shape with the stem passing through the stack to hold the strips in vertical position. The strips are of any usual type usually with the brass strip 65 on the inside to facilitate the easy distortion or partial straightening of the strips under increased heat. The action is multiplied by the arrangement of one on the other and the closing and opening of the valve 21 is prompt 70 and positive. For preventing the thermostatic strips 24 from getting out of alignment and insuring their turning together if they turn, I place a strip 25 so that it engages the sides of the strips 24 and bend 75 the ends 26 so that their perforations 27 receive the stem 16.

The stem rests in the bottom of the recess in the boss 28 and when adjustment is desired the screw 29 can be placed in lieu of a 80 solid bottom and the valve 21 thus located relative to the seat 22.

The U-shaped thermostatic strips 24 are arranged in vertical alignment and when they expand their points of contact are 85 shifted to one side of the axis of the stem 16. The expansion of the strips is not constant and even but slightly vibrative. This, coupled with the loose fit of the stem in the boss 28, gives to the valve 21 a shaky vibrating 90 ascent as it closes on the seat 22. This dislodges any minute particles on the valve seat, rubs the valve to clean it of particles and works the valve into its seat which is different and of marked advantage over a straight 95 push. When the valve 21 is finally seated the thermostatic members are supported at their ends, one on the other. They are kept in alignment by the strip 25 but the parts can freely revolve and this also tends to keep the 100

valve and valve seat clear of dust and small particles and thus insure a tight seal when the valve is shut.

In the top of the valve I place a breather and this is usually installed in a chamber 30 formed by the cap 31 and the recessed top of the plate 15. This chamber is made rather broad to prevent water being retained therein by capillary attraction. The cap has one or more outlets 32.

Below the outlet 32 and above the opening 22 is the plate 33 securely held and usually of stiff sheet metal. On this plate is a flap 34 of very thin material and it is secured by 15 means such as the rivet 35.

The material of the flap is of a nature to flutter easily under pressure from within the valve so that air can pass out of the hole 36 in the plate 33. Under the influence of a slight current in the other direction, that is from the atmosphere the strip 34 will close the opening 36. But I have gone further and provided a dished or recessed area 37 around the hole 36 and this allows the plate or 20 flap 36 to be depressed into the area 37 under strong pressure. On excess pressure, however, which requires the admission of some air, the flap 34 is sucked in until it engages the very edge of the opening 36 and enough 25 distortion or wrinkling of the flap 36 takes place to allow air to pass through these slightly uneven places. The material that I find best adapted for this function in the flap is a thin sheet of mica.

35 The chamber 33 acts as a condensation chamber and its broad form facilitates the flowing of the water back into the casing as compared with a small long hole with its capillary attraction.

40 Various changes can be made without departing from the scope of the invention.

I claim:—

1. An air valve for radiators having a casing with an outlet opening, and a thermostatic valve to close said opening, and a breather valve above said opening, the breather valve being flexible and secured at one end on a dished valve seat so that it is freely opened under pressure from within 45 the valve casing, and pressed into the dished valve seat and thereby slightly opened at its free end under excessive pressure from the outside.

2. An air valve for radiators having a casing with an outlet opening, a thermostatic valve for closing the opening, a breather above the outlet opening and comprising a plate with an opening therein, and a flap on the opening, said flap consisting of a thin 55 strip of flexible material to freely open under outward pressure and adapted to be distorted to an irregular form and thereby opened under excess inward pressure.

3. An air valve for radiators having a casing with an outlet opening, a thermostatic

valve for closing the opening, a breather above the outlet opening and comprising a plate having an opening with its edges dished downwardly and a flap of thin mica secured so as to rest on the opening.

4. An air vent comprising a casing having a valve seat, a valve to close the seat, a stem on which the valve is mounted and a series of aligned U-shaped thermostatic strips on the stem and supporting the valve and acting to close the valve on an increase in temperature, the closed ends of the members lying on the same side of the stem.

5. An air vent comprising a casing having a valve seat, a valve to close the seat, a stem 80 supporting the valve, a dome supported on the stem, the stem supporting the valve in normal position, and a vertically aligned series of horizontally arranged U-shaped strips of thermostatic material to close the valve 85 and having their closed ends on the same side of the stem.

6. An air vent comprising a casing having a valve seat, a valve to close the seat, a dome supported on the valve, a stem supporting the valve in normal position, a vertically aligned series of horizontally arranged U-shaped strips of thermostatic material to close the valve, and a screw in the casing and supporting the stem, the screw being accessible from the outside of the casing whereby 95 the valve can be adjusted.

7. An air vent comprising a casing having a valve seat at the top, a stem to close the seat, a rod on which the stem is slidably supported, a disk on the rod, a set of U-shaped thermostatic strips abutting on the stem and on the disk, and a screw in the casing and accessible from the outside, the rod resting on the screw.

8. An air vent comprising a casing having a valve seat therein, a valve for closing the valve seat, means for supporting the valve from beneath and giving it limited side movement, and a series of thermostatic members 110 which contact, when expanded, out of alignment with the axis of the valve, said series acting to raise the valve to its seat under the influence of increased temperature.

9. An air vent comprising a valve casing 115 with a valve seat therein, a loosely supported valve under the seat and adapted to close it and a series of thermostatic members which abut and which contact under expansion at points out of line with the axis of the valve 120 to close the valve with a slight vibration.

In testimony whereof I affix my signature.

EARL S. ALEXANDER.
